UNITED STATES PATENT OFFICE.

JOHN E. MITCHELL, OF SPRINGFIELD TOWNSHIP, SUMMIT COUNTY, OHIO.

SAFETY-CATCH FOR ELEVATORS.

1,316,498.

Specification of Letters Patent. Patented Sept. 16, 1919.

Application filed August 6, 1918. Serial No. 248,520.

To all whom it may concern:

Be it known that I, JOHN E. MITCHELL, a citizen of the United States, residing at Springfield township, Summit county, Ohio, 5 have invented new and useful Improvements in Safety-Catches for Elevators, of which the following is a specification.

This invention relates to improvements in safety devices for elevators, and the object 10 of the invention is to provide a locking device which will move to its operative position to arrest the descent of the elevator in case that the lifting cable of the elevator is broken or suddenly loosened. A further object 15 of the invention is to provide a simple and effective device for this purpose which may be applied to practically any elevator and which will insure against the unintentional descent thereof.

20 With the foregoing and other objects in view, the invention consists in the novel construction, combination and arrangement of parts constituting the invention to be hereinafter specifically described and illustrated 25 in the accompanying drawings which form a part hereof wherein is shown the preferred embodiment of the invention, but it is to be understood that changes, variations and modifications can be resorted to which come 30 within the scope of the matter hereinafter claimed.

In the drawings in which similar reference numerals indicate like parts in the different figures,

35 Figure 1 is a vertical sectional view taken approximately on line 1 of Fig. 3.

Fig. 2 is a sectional view taken approximately on line 2 of Fig. 1, and

40 Fig. 3 is a sectional view taken approximately on line 3 of Fig. 1.

The fixed portion of the elevator comprises the usual frame comprising upright posts 1 arranged at the corners of an imaginary rectilinear figure and stiffened and reinforced by means of cross bars 2 in the usual manner. As a part of the frame of the elevator shaft are a pair of guides 3 oppositely disposed in the usual manner and preferably composed of wood. The guides 45 and frame are of the usual construction and further description thereof is believed to be unnecessary. For brevity of description the movable part of the elevator will be designated as a cage and it embodies a lower 50 platform 4 provided with cutaway portions or notches to receive the guides 3. Above

the platform 4 is a head 5 preferably cruciform in shape and provided with notches 6 to receive the guides 3 to prevent sidewise movement of the entire cage during its vertical movement. The platform 4 is supported from the head 5 by means of a pair of parallel rods 7 positioned closely adjacent to the guides 3 and connected both with the head 5 and with the platform 4. The platform 4 is furthermore connected with the head by means of braces 8 which pass upwardly over the upper face of the head 5 and are held in position by means of clips or holding members 9. Secured to each of 60 the upright bars 7 by means of clamps 10 are horizontal bars 11 the outer ends of each of which are provided with bearings 12 the bearing at one end of each bar being oppositely disposed to the corresponding bearing of the other bar and in these pairs of bearings are mounted parallel shafts 13. Secured to the faces of the head 5 are brackets 14 the lower ends of which are provided with bearings for the shafts 13 so as 65 to support them intermediately of the bearings on the ends of the bars 11. Mounted on both ends of both shafts 13 are toothed wheels 15 each of which is provided with a cutaway or flat portion 16 unprovided with 70 teeth and these portions are normally adapted to be out of contact with the guides 3 when in their inoperative positions. Each toothed wheel is oppositely disposed and on opposite sides from the toothed wheel on 75 the other shaft. These toothed wheels are so arranged that when rotated the teeth will engage or dig into the wooden guides 3 and prevent downward movement of the cage.

80 In order to insure the interengagement of 85 the toothed wheels 15 with the sides of the guides 3 there is mounted on each of the shafts 13 preferably centrally thereof an arm 17 each bearing at its outer end a counterweight 18. These arms 17 are capable of a 90 vertical rocking movement in unison with the rotation of the shafts 13 and in order to limit this movement there is provided at each side of the head 5 a plate 19 provided with a slot 20 through which slots the arms 100 17 extend, the outer ends of the slots being closed by portions 21 which form stops or abutments for limiting the downward movement of the arms 17 and the counterweights 18. The arms 17 are drawn downwardly to 105 110 their inoperative position by means of coiled springs 22 extending between anchorages on

the arms 17 and the portions 21 of the plates 20. The central portion of the head 5 is provided with an anchorage 23 for a chain or other flexible member 24 which terminates 5 in a ring 25 to which is connected a lifting cable 26, by means of which the cage is lifted. The ring 25 is connected with each of the arms 17 by means of flexible connections such as chains 27 which are united 10 preferably with the outer portions of the arms near the counterweights 18 and are designed to raise the arms 17 upwardly to bring the toothed wheels 15 to their inoperative position when the cable 26 is taut as 15 clearly shown in Fig. 1. In case of a break in the lifting cable 26 or a sudden slackening thereof the counterweights swing outwardly and downwardly on their pivots, the shafts 13, and rotate the latter causing the teeth of 20 the wheels 15 to engage the sides of the guides 3 and set up a gripping action for arresting further descent of the cage. The downward movement of the arms 17 due to a slackening or breaking of the lifting cable 25 26 is aided by the coiled springs 22 so as to cause as far as possible an instantaneous movement downwardly of the arms 17 to rotate the wheels 15 to throw the teeth of the wheels 15 into quick contact and locking 30 position with respect to the guides 3.

I claim:

The combination in an elevator of a pair 35 of guides, a cage adapted to slide thereon, said cage embodying a cross head, a shaft mounted on each side of said cross head at

a point spaced downwardly thereof, an arm mounted on each of said shafts and arranged when oscillated to partially rotate the former, a lifting cable connected centrally of said cross head, chains connecting said lifting cable with the outer portions of said arms and arranged to move said arms to their upper inoperative position when said cable is in a taut condition and synchronize with the upward movement of said cable, a 40 toothed wheel mounted on each end of each of said shafts arranged when rotated in unison with its supporting shaft to establish gripping engagement with one of said guides for holding said cage against downward 45 movement, a portion of each of said toothed wheels being unprovided with teeth and having a flat portion arranged to lie parallel to and slightly removed from the face of a guide during the inoperative or upper position of said arms, an anchor fixed to each side of said cross head and extending laterally therefrom with an unsupported outer end and having a slotted opening therein extending from the cross head to a point adjacent the outer end thereof and through which the adjacent arm extends at all times for limited movement, and a spring extending between the free outer end of each anchor and the adjacent arm for normally moving 50 the arm to its lowered inoperative position. 55

In testimony whereof I have hereunto set my hand.

JOHN E. MITCHELL.
